Primary Examiner — Jack Reickel

Assistant Examiner — Bobby W Jones, II

(57) **CLAIM**

The ornamental design for a filter arm support, as shown and described.

DESCRIPTION

FIG. 1 is a perspective view of a filter arm support showing our new design;

FIG. 2 is a front view thereof;

FIG. 3 is a left view thereof;

FIG. 4 is a right view thereof;

FIG. 5 is a back view thereof;

FIG. 6 is a top view thereof; and,

FIG. 7 is a bottom view thereof.

The broken lines shown in the figures depict portions of the filter arm support that do not form part of the claimed design.
